Primary Examiner—Louis S. Zarfas**Assistant Examiner**—Monica A. Weingart**Attorney, Agent, or Firm**—Fish & Richardson P.C.**[57]****CLAIM****The ornamental design for a decorative arrangement on a child's shoe surface, as shown and described.****DESCRIPTION****FIG. 1** is a front perspective view of a decorative arrangement on a child's shoe surface showing my new design;**FIG. 2** is a top plan view thereof;**FIG. 3** is a left side elevational view thereof;**FIG. 4** is a right side elevational view thereof; and,**FIG. 5** is a front elevational view thereof.

The broken line showing of a portion of a child's shoe is environmental only and forms no part of the claimed design. The decorative arrangement on a child's shoe surface of my new design is not seen in rear or bottom elevational views.
